UNITED STATES PATENT OFFICE.

PHILIP V. TIPPET, OF CUYAHOGA FALLS, OHIO, ASSIGNOR TO THE VAUGHN MACHINERY COMPANY, OF CUYAHOGA FALLS, OHIO, A CORPORATION OF OHIO.

WIRE-DRAWING MECHANISM.

Application filed April 9, 1924. Serial No. 705,223.

The present improvements, relating, as indicated, to wire drawing mechanism, have more particular regard to the means provided for driving the drawing block or drum, whereby the original rod is reduced to the desired diameter. Whether in a continuous wire drawing bench; when a series of such drums is regularly employed, the rod or wire being passed through a corresponding series of dies, one located in advance of each such block, or in a single drum machine having a single die associated therewith, the blocks are ordinarily mounted on the upper ends of vertical shafts or spindles and these are driven from a back shaft through suitable interposed gearing.

I am aware that it has heretofore been proposed in so-called continuous wire drawing benches to substitute for a drive of the type just described an individual motor drive for the separate blocks or drums and then rely upon a change in speed of the several motors, such speed being controlled by familiar motor-control devices, to produce the necessary variation in speed of rotation of such block; however, the practical difficulties involved in applying a separate motor drive to the individual blocks is not as simple a matter as might be supposed and no commercial success has been attained in the utilization of such individual drive.

The object of the present invention, accordingly, is the provision of a self-contained unit comprising an individually driven wire block suitably mounted on a stand and having a motor connected therewith through a worm and worm gear drive housed in such stand and having associated with the latter the necessary devices for controlling the speed of the motor and thus of the particular block driven thereby. The units thus provided being self contained, any desired number may be assembled to form a drawing bench with the requisite number of blocks or drums to meet the special requirements of the mill being designed.

To the accomplishment of the foregoing and related ends, the invention, then, consists of the means hereinafter fully described and particularly pointed out in the claims, the annexed drawings and the following description setting forth in detail certain mechanism embodying the invention, such disclosed means constituting, however, but

one of various mechanical forms in which the principle of the invention may be used.

In said annexed drawings:

Fig. 1 is a plan view of one of the individually motor driven self-contained units of my improved wire drawing mechanism; 60 Fig. 2 is a front elevation of the same, as viewed from the left in Fig. 1; Fig. 3 is a horizontal section of such unit taken on the plane indicated by the line 3—3, Fig. 4; and Fig. 4 is a vertical central section of the 65 same, the plane of the section being indicated by the line 4—4, Fig. 1.

As best indicated in Figs. 3 and 4, the main frame 1 of my improved single block unit is a rectangular box-like structure, preferably formed of an integral casting that is firmly supported by means of feet 2 on a substantial base 3. The bottom or floor 4 of such box-like frame slopes towards one side, i. e., the left as shown in Fig. 4, and 75 the lateral walls of such frame are imperforate save for a transverse opening 5 in the front wall which is closed in the assembled condition of the parts by a cover plate 6. Note should also be taken of smaller openings 7 and 8 in the rear and front walls, respectively, therewith are connected lubricant supply and discharge lines 9 and 10, by means of which lubricant may be maintained at any desired height in the chamber thus 80 provided within the hollow frame 1.

The top of the hollow frame 1 is closed by a heavy plate 12 that not only forms a cover for such box, but also serves to support a bearing 13 for the vertical spindle 14, 90 the upper end of which projects above such plate and carries the drawing block or drum 15. It will be noted that this bearing 13 is constructed to take the axial thrust of the spindle in both directions, as well as to support said spindle laterally, and that the lower end of the spindle is simply journaled laterally in a bearing 16 provided on the floor 4 of the hollow frame 1, radial ribs 17 on such floor serving to strengthen the latter 100 and brace such bearing.

A supplemental top or table 20 is supported by the frame 1, being fitted over the upper portion of such frame so as to lie on substantially the same level as top plate 12, 105 and rising from such table is a circular flange 21 that surrounds the lower depending flange portion 22 of the block 15. The form

of table 20 is preferably rectangular, as shown in Fig. 1, such table including a lateral extension 23 at one side thereof that serves to bridge the space between such table 5 and the next adjacent table where a plurality of units are placed side by side to form a drawing bench. An angularly projecting bracket 24 is also provided with its top substantially on the level of the table 20 to support the usual die-holder 25 and guide 26 through which the rod or wire passes to such block on its way to the drum 15.

The base 3 on which frame 1 is supported, as hereinbefore described, is extended to 15 the rear and on such extension 30 is mounted a motor 31, the spindle 32 of which is connected by means of a flexible coupling 33 with a horizontal shaft 34 that is journaled in suitable bearings 35 and 36, provided in the corresponding side of the frame 20 1 of the machine. The side in question is the one in which the transversely extending opening 5 occurs, as heretofore described, and the bearings 35 and 36 are held in suitable complementary recesses formed at each end of 25 such opening and the adjacent portions of the cover plate 6. The portion of shaft 34 lying intermediate of said bearings is provided with a worm 37 that meshes with a 30 worm gear 38, keyed or otherwise non-rotatably mounted on the vertical shaft 14 that carries the block 15. The worm and worm gear drive for the shaft thus provided, it will be seen, is wholly contained 35 within the hollow interior of frame 1 which not only protects such gearing but also permits a body of lubricant to be maintained at a sufficient elevation in such hollow frame interior to partly or wholly submerge the 40 gearing and thus insure thorough lubrication at all times. Bearing 36 and the corresponding end of worm shaft 34 is sealed by means of a cap 39 (Fig. 3), while a gland 40 similarly seals the other end of said shaft 45 where it passes through bearing 35, thus preventing any escape of lubricant except by way of discharge pipe 10.

The supply of current to the motor 31 is controlled in the first place by switch box 50 41, conveniently mounted at the rear end of the table extension 23 and including a motor field rheostat with field rheostat relay operated by means of a handle 42; while a grid resistor 43 and a controller 44 of 55 standard type are mounted on the base extension 30 laterally adjacent motor 31, such controller being operated through a link 45 from a lever 46 pivotally attached to the table extension 23 and extending upwardly 60 through an elongated recess 47 therein.

The guide 26 is in fact a safety device constituting one end of a lever that is suitably connected with a switch of standard 65 type in the motor circuit arranged to apply dynamic braking to the motor. The entire

machine can thus be stopped within five or six inches travel on the block by a slight pull on device 26, and anyone caught in a loop of the wire cannot avoid striking this device and consequently stopping the block 70 before any injury can be done. The device furthermore is in easy reach for manual operation at any time. Dynamic braking is also applied to the motor whenever the main control switch is operated by lever 46, the 75 action being the same as when the safety device is operated.

The finished coil of wire on the drum will of course be removed in the usual way with a suitable stripper (not shown), this forming no part of the machine, proper.

The construction of the machine is particularly designed to facilitate the assembly and disassembly of the parts. By removing plate 6, the worm shaft 34 along with 85 the bearings associated with its respective ends may be bodily removed, and similarly by unbolting top plate 23, it together with the vertical spindle 14 and its bearings may be directly withdrawn from the hollow 90 frame 1. The flexible coupling 33 between the motor and worm shaft 34 is furthermore designed so that said shaft can be removed in the manner just described without backing the motor off.

From the foregoing description it will be seen that my improved unitary drawing block is of extremely compact and yet sturdy construction; also that such unit is entirely self-contained, including as it does 100 not merely the drawing block proper with necessary accessories, but a motor whereby such block is independently driven. The devices for controlling the operation of such motor, and thereby the speed of rotation of 105 the block, are so disposed as to be within a convenient reach of the operator attending the block or series of blocks where a number of the latter are arranged in a row. More particular attention, however, is directed to the construction of the hollow frame 1 and the worm drive that is mounted therein so as wholly to be contained 110 within the interior of such frame. The arrangement of the bearings for the worm 115 shaft 34 is such as to insure not only proper alignment of the worm with the worm gear, but also the thorough lubrication of such bearings and gearing at all times.

The use of worm gears is preferred since 120 by immersing these in oil, all noise and vibration are practically eliminated. Furthermore, on account of the teeth being always in contact, the wire is pulled more steadily and smoothly through the die than is the case with straight tooth gears. This smooth pull, at the same time decreases the wear on the dies.

Other modes of applying the principle of 125 my invention may be employed instead of 130

the one explained, change being made as regards the mechanism herein disclosed, provided the means stated by any of the following claims or the equivalent of such stated means be employed.

I therefore particularly point out and distinctly claim as my invention:—

1. In wire drawing mechanism, a self-contained unit including a hollow frame, a support bridging the top of said frame, a vertical spindle projecting above and journaled in said support, the lower end of said spindle being journaled in the bottom of said frame, a drum carried by the upper, projecting end of said spindle, a transverse shaft aligned with the one side of said frame and journaled at its respective ends in the adjacent walls of said frame, a worm gear on said spindle, and a worm on said shaft meshing with said gear.

2. In wire drawing mechanism, a self-contained unit including a hollow frame, a support bridging the top of said frame, a vertical spindle projecting above and journaled in said support, being held against axial thrust as well as laterally therein, and the lower end of said spindle being laterally journaled in the bottom of said frame, a drum carried by the upper, projecting end of said spindle, a transverse shaft aligned with the one side of said frame and journaled at its respective ends in the adjacent walls of said frame, a worm gear on said spindle, and a worm on said shaft meshing with said gear.

3. In wire drawing mechanism, a self-contained unit including a hollow frame with laterally imperforate walls save for an opening in one side, a removable plate closing such opening, a support bridging the top of said frame, a vertical spindle projecting above and journaled in said support, the lower end of said spindle being journaled in the bottom of said frame, a drum carried by the upper, projecting end of said spindle, a transverse shaft aligned with the opening in the one side of said frame and journaled at its respective ends in the adjacent side-walls of said frame, a worm gear on said spindle, and a worm on said shaft meshing with said gear.

4. In wire-drawing mechanism, a self-contained unit including a hollow frame with laterally imperforate walls save for an opening in one side, a removable plate closing such opening, a top-plate for said frame, a vertical spindle projecting above and journaled in said top-plate, the lower end of said spindle being journaled in the bottom of said frame, a drum carried by the upper, projecting end of said spindle, a transverse shaft aligned with the opening in the one side of said frame and journaled at its respective ends in the adjacent side-walls of said frame, a worm gear on said spindle, and a worm on said shaft meshing

a worm on said shaft meshing with said gear.

5. In wire-drawing mechanism, a self-contained unit including a hollow frame with laterally imperforate walls save for an opening in one side, a removable plate closing such opening, said plate and the adjacent portions of the wall being formed with complementary recesses, transversely aligned bearings held in such recesses, a top-plate for said frame, a vertical spindle projecting above and journaled in said top-plate, the lower end of said spindle being journaled in the bottom of said frame, a drum carried by the upper, projecting end of said spindle, a shaft journaled in said transversely aligned bearings, a worm-gear on said spindle, and a worm on said shaft meshing with said gear.

6. In wire-drawing mechanism, a self-contained unit including a hollow frame with laterally imperforate walls save for an opening in one side, a removable plate closing such opening, said plate and the adjacent portions of the wall being formed with complementary recesses, transversely aligned bearings held in such recesses, a top-plate for said frame, a vertical spindle projecting above and journaled in said top-plate, the lower end of said spindle being journaled in the bottom of said frame, a drum carried by the upper, projecting end of said spindle, a shaft journaled in said transversely aligned bearings and extending through one such bearing beyond said frame, a stuffing box associated with said last-mentioned bearing, a cap externally closing off the other aligned bearing, a worm-gear on said spindle, and a worm on said shaft meshing with said gear.

7. In wire-drawing mechanism, a self-contained unit including a base, a hollow frame secured to said base, a vertical spindle rotatably mounted in said frame and projecting thereabove, a drum carried by the upper end of said spindle, a transverse shaft located and journaled at its respective ends in said frame, one such shaft end projecting without said frame, a worm-gear on said spindle, a worm on said shaft meshing with said gear, a motor mounted on said base without but adjacent said frame, the spindle of said motor being approximately aligned with said shaft, and a coupling connecting the projecting end of the latter with such motor spindle.

8. In wire-drawing mechanism, a self-contained unit including a hollow frame, a vertical spindle rotatably mounted in said frame and projecting thereabove, a drum carried by said spindle at its upper end, a transverse shaft journaled at its respective ends in said frame and laterally removable from said frame, a worm gear on said spindle, and a worm on said shaft meshing

with said gear, said worm and gear lying within said frame, the latter being constructed and arranged to form an oil-tight housing for said gearing.

5. 9. In wire drawing mechanism, a self-contained unit including a hollow frame, a removable support bridging said frame, a vertical spindle projecting above and journaled in said member, and a drum carried by the upper projecting end of said spindle, the lower end of the latter being journaled in the bottom of said frame and said spindle being vertically removable from said frame along with said member.
10. 10. In wire drawing mechanism, a self-contained unit including a hollow frame, a removable support bridging said frame, a vertical spindle projecting above and journaled in said member, being held against axial thrust as well as laterally therein, and a drum carried by the upper projecting end of said spindle, the lower end of the latter being journaled in the bottom of said frame and said spindle being vertically removable from said frame along with said member.
11. 11. In wire-drawing mechanism, a self-

contained unit including a hollow frame, a removable top plate for said frame, a vertical spindle projecting above and journaled in said top-plate, and a drum carried by the upper projecting end of said spindle, the lower end of the latter being journaled in the bottom of said frame and said spindle being vertically removable from said frame along with said top plate.

12. 12. In wire-drawing mechanism, a self-contained unit including a hollow frame, a removable top plate for said frame, a vertical spindle projecting above and journaled in said top-plate, a drum carried by the projecting end of said spindle, a transverse shaft journaled at its respective ends in said frame and laterally removable along with its bearings from said frame, a worm-gear on said spindle, and a worm on said shaft meshing with said gear, said spindle being vertically removable from said frame along with said top-plate, and said frame constituting a gear-case for said gearing, including the lower spindle-bearing.

Signed by me, this 4 day of April, 1924
PHILIP V. TIPPET.
